UNITED STATES PATENT OFFICE.

WALTER ZEBULIN BRANNON, OF BRAZOS, TEXAS.

WIRE-STRETCHER.

SPECIFICATION forming part of Letters Patent No. 693,227, dated February 11, 1902.

Application filed June 21, 1901. Serial No. 65,454. (No model.)

To all whom it may concern:

Be it known that I, WALTER ZEBULIN BRANNON, a citizen of the United States, and a resident of Brazos, in the county of Palo Pinto 5 and State of Texas, have invented a new and Improved Wire-Stretcher, of which the following is a full, clear, and exact description.

The purpose of the invention is to provide a simple form of device for stretching wire, 10 said device being adapted for attachment to a post or other support and to the wire to be stretched, and to so construct the device that through the movement of a lever and two gripping-arms, the latter traveling upon the element to which the wire is attached, said element by one movement of the lever will be carried in a direction to place the wire under renewed tension, one gripping-arm acting to bring about such a result, the other gripping- 15 arm acting to hold the wire under tension while the actuating-arm is advanced for another grip, the locking-arm being free to travel upon the wire-holding element while the actuating-arm is in action.

20 The invention consists in the novel construction and combination of the several parts, as will be hereinafter fully set forth, and pointed out in the claims.

Reference is to be had to the accompanying 25 drawings, forming a part of this specification, in which similar characters of reference indicate corresponding parts in all the figures.

Figure 1 is a plan view of the improved wire-stretcher. Fig. 2 is a transverse section 30 taken on the line 2 2 of Fig. 1. Fig. 3 is a transverse section taken on the line 3 3 of Fig. 1, and Fig. 4 is a detail view of a portion of the link connected with the lever and a plan and partial sectional view of the actuating-arm carried by the said link.

40 A represents a body-bar, which is provided with an eye 10 at one end, to which eye a section 11 is connected, adapted to carry any form of wire-gripping device. A block 12 is mounted to slide on the body-bar A, which body-bar is preferably circular in cross-section, and at what may be termed the "rear" end of the block 12 a hook 14 is pivotally attached through the medium of a link 13, the 45 hook being adapted for engagement with a post of a wire fence or any near-by support.

At the opposite or forward end of the block 12 a loop 15 is formed, which receives the free end of what I term a "locking-arm" 16, which arm has an aperture extending through from 55 face to face to accommodate the body-bar A, and a washer 17 is loosely mounted on the body-bar, having bearing against the end of the block 12 at which the loop 15 is located, while a spring 18 is coiled around the body- 60 bar, having bearing against the said washer and the apertured portion of the said locking-arm, normally holding the locking-arm 16 at an inclination in direction of the block 12.

A lever 19 is fulcrumed upon the block 12, 65 and an actuating-arm 20 is apertured to receive the body-bar A at a point in advance of the locking-arm, the said actuating-arm being pivotally connected at one end with a link 21, which is pivotally secured to the lever 19, as is best shown in Fig. 1. The actuating-arm 20 is held at an inclination away from the sliding block 12 or at an inclination the reverse of the locking-arm 16 through the medium of a spring 22, having bearing against 70 the inner face of the actuating-arm and a bearing upon the link 21.

In operation the hook 14 is placed in engagement with a post or a similar support adjacent to the strand of wire to be stretched, 80 and the wire is secured in the clamp carried by the section 11, above referred to, and connected with the body-bar A. The lever 19 is then given a throw in direction of the wire to be stretched, causing the actuating-arm 20 to 85 slide on the body-bar toward the wire, while the locking-arm 16 remains stationary, holding the body-bar A in the same position. Next the lever 19 is carried in the reverse direction or away from the wire, and at such 90 time the actuating-arm 20 will bite upon the body-bar A and will carry the said body-bar away from the wire, placing it under tension, the locking-arm being at such time released from gripping engagement with the body-bar, 95 permitting the said body-bar to move in the direction mentioned; but as soon as the lever 19 is carried in direction of the wire to cause the actuating-arm to obtain another hold on the body-bar A the locking-arm 16 will hold 100 the body-bar from moving, thus maintaining the tension already applied to the wire.

Having thus described my invention, I claim as new and desire to secure by Letters Patent—

1. A wire-stretcher consisting of a body-bar adapted for connection to the end of a wire to be stretched, a block mounted to slide on the body-bar, a guide-loop connected with one end of said block, a post-gripping device carried at the other end of said block, a lever pivoted to the sliding block between the ends of the latter, a link pivoted to said lever, locking and actuating arms mounted for sliding and gripping engagement upon the body-bar, the actuating-arm being attached to the said link and the free end of the locking-arm engaging the loop on the said sliding block, and a spring on the body-bar, between the sliding block and the locking-arm, substantially as described.
2. In a wire-stretcher, a body-bar adapted for attachment to one end of a wire to be stretched, a block held to slide on the body-bar, a hook pivotally connected with one end of said sliding block, a loop pivoted to the opposite end of said sliding block, a spring-controlled locking-arm mounted to slide on the body-bar and grip the same, the free end of said locking-arm extending through the loop on the sliding block, a lever pivoted to the sliding block at a point between the pivoted hook and the loop, a link connected at one end with said lever, and a spring-controlled actuating-arm pivoted to the other end of said

link and having sliding and gripping engagement with the body-bar, the locking and actuating arms having inclination in opposite directions.

3. In a wire-stretcher, the combination, with a body-bar having means for attachment to an end of a wire to be stretched, a block mounted to slide on the body-bar, a hook having a link connection with one end of the block, a guide-loop located at the opposite end of the block, a locking-arm having an aperture through which the body-bar passes, the free end of the locking-arm entering the said guide-loop of the block, a washer loosely mounted on the body-bar and engaging that end of the block at which the loop is located, and a spring coiled around the body-bar and bearing against the said washer, and the apertured portion of said locking-arm, of a lever pivoted upon said block, a link pivoted to said lever, and a spring-controlled actuating-arm pivoted to said link, the actuating-arm being provided with an aperture through which the body-bar passes, the locking and actuating arms being normally inclined in opposite directions, as and for the purpose specified.

In testimony whereof I have signed my name to this specification in the presence of two subscribing witnesses.

WALTER ZEBULIN BRANNON.
